FEEDER

Eugene Martin, Wesleyville, Pa., assignor to Read Standard Corporation, a corporation of Delaware

Application June 5, 1947, Serial No. 752,849

1 Claim. (Cl. 214—17)

1

The invention relates to material feeding means and particularly to a reciprocating piston type feeding mechanism for delivering material to a receiver from a source of supply, in which a pressure differential exists between the receiver and the source of supply.

It is an object of the invention to provide an improved feed mechanism of the type described wherein an effectual seal is maintained at all times against escape of pressure past the feed mechanism.

A further object of the invention is to provide an improved feed mechanism of the type described wherein friction incident to operating the feed mechanism is minimized, while maintaining an effective seal against escape of pressure past the feed mechanism.

Another object of the invention is to provide improved feed mechanism of the type described wherein discharge of the material from the feed piston into the pressurized receiver is facilitated; and it is a further object to provide effective venting means for releasing the pressure, trapped in the feed piston, on the retracting stroke of the piston prior to recommunication of the feed piston with the source of material supply.

Further objects of the invention are to provide an improved feeding device that is easily assembled, conveniently arranged for replacement of parts and for lubrication; and generally to provide a practical and efficient feeding device.

Additional objects, advantages and features of the invention reside in the construction, arrangement and combination of parts, as will be understood from the preferred and practical embodiment of the invention hereinafter described and illustrated in the accompanying drawings, in which

Figure 1 is a diametric view of the invention with a quarter section broken away and shown in section;

Figure 2 is a horizontal central section through the invention with parts thereof shown in elevation;

Figure 3 is a sectional view taken on the line 3—3 of Figure 2;

Figure 4 is a sectional view taken on the line 4—4 of Figure 2;

Figure 5 is a fragmentary vertical longitudinal central sectional view of the invention showing the discharge outlet and adjacent parts of the novel material feeding mechanism; and

Figure 6 is a sectional view taken on the line 6—6 of Figure 2.

The invention is described hereinafter, as a 55 cal casing 11.

2

feed mechanism for finely divided coal, however, it will become apparent that it is capable of feeding various types of materials from a source of supply to a point of discharge, particularly where a differential in pressure exists between said source and discharge.

The coal pump 10 comprises a hollow cylindrical casing 11, preferably formed for a reason later explained, by a pair of end to end related rigidly connected cylindrical housing sections 12 and 13 secured together by means of the bolts 14. The section 12 is provided in its top with an inwardly extending coal intake spout 15 and the section 13 is provided in its bottom with an inwardly extending coal discharge spout 16, the intake spout being best shown in Figures 1 and 3, and the discharge spout in Figures 5 and 6. The intake and discharge spouts are offset or spaced a distance apart longitudinally of the coal pump.

20 A boss 17, formed with the housing section 12, surrounds the intake spout 15, to which a coal hopper (not shown) is suitably secured whereby coal will feed by gravity from the hopper through the intake spout 15. A connecting discharge spout 18, preferably formed integral with the housing section 13, registers with the discharge spout 16 and is adapted to be connected with a pressurized receptacle (not shown) into which coal drops by gravity from the coal pump 10.

25 A crank case 19 is arranged in end to end relation with the cylindrical casing 11, and is provided at its end adjacent the casing 11 with a transverse wall 20 through which it is secured to the inturned flange 21 of the housing section 12 of casing 11 by means of bolts 22. The opposite end of the crank case 19 is provided with a crank case cover 23 suitably secured, as by the bolts 24, to the crank case 19. The end of the casing 11 opposite the crank case 19 is closed by a hollow cover 25 secured to the end wall of the housing section 13 by suitable means, as by bolts (not shown), which pass through the outwardly projecting flange 27 of the cover 25.

30 A piston 28, mounted to reciprocate in the casing 11, includes a head 29 having a rectangular shaped bore 30 extending vertically therethrough and arranged in one extreme position of the piston 28 to communicate with the intake spout 15 and in the other extreme position of the piston 28 to communicate with the discharge spout 16. Threaded on the periphery of the opposite faces 31 and 32 of the head 29 are the longitudinally extending cylindrical sleeves 33 and 34, respectively, arranged coaxial with the cylindri-

The diameter of the sleeves 33 and 34 is such that a slight clearance is provided between the periphery of the sleeves and the inner ends of intake and discharge spouts 15 and 16 as the piston 28 reciprocates. The outer surface of the piston 28 is thus spaced from the inner wall of the cylindrical casing 11 forming an annular passage 35, thereby minimizing scoring, abrasion and freezing of the piston 28 in the cylindrical casing 11 by the coal dust and particles that find their way between the piston and casing during operation of the coal pump.

The head 29 of the piston 28 is provided on its opposite faces 31 and 32 with the longitudinally extending piston rods 36 and 37, respectively, preferably formed integral with the head 29. The rod 36 is mounted to slide in a bearing 38 formed with the transverse wall 20 of the crank case 19, and the rod 37 is mounted to slide in a bearing 39 formed with the hollow cover 25.

The piston 28 is operated from a crankshaft 40 extending transversely of the coal pump 10 and journaled in the bearings 41 and 42. The bearings 41 and 42 are mounted, respectively, in the removable bearing covers 43 and 44 which are secured in suitable manner, as by bolts 45, in the sides of the crank case 19 of the coal pump 10.

A pair of connecting rods 46 and 47, one at each side of the piston rod 36, rotatably mounted at one of their respective ends on a crank 48, preferably formed integral with the crank shaft 40, project through respective vertically elongated slots 49 and 50 and are oscillatably mounted at their respective opposite ends on the respective opposite ends of a transversely extending wrist pin 51 carried by the piston head 29. The crank 48 is formed with a throw equal to one half the distance between the intake spout 15 and discharge spout 16, so that upon reciprocation of the piston 28 through the crankshaft 40 and connecting rods 46 and 47, the bore 30 of the piston head 29 will communicate with the intake spout 15 at one extreme position of the piston 28 and will communicate with the discharge spout 16 at the other extreme position of the piston 28.

For a purpose to be later explained, the piston 28 is preferably provided with coal receiving insert 52 fitting within the bore 30 of the piston head 29 and retained therein by engagement of outwardly projecting shoulders formed with the insert 52 and inwardly projecting shoulders formed with the sleeves 33 and 34, respectively. The insert 52 is readily placed in position or removed by threading the sleeves 33 and 34 back on the piston head 29. The insert 52 is open at its upper end through which it receives coal from the intake spout 15 and is open at its lower end through which the coal is discharged into the discharge spout 16.

Since, as previously stated, clearance is provided between the inner ends of the intake and discharge spouts 15 and 16 and the outer surface of the sleeves 33 and 34, a pressure seal is provided about the sleeve 34 between the non-pressurized intake spout 15 and the pressurized discharge spout 16 to eliminate escape of air from the pressurized discharge spout 16 through the said clearances and consequent blow back of the coal therethrough. The pressure seal is formed by a plurality of non-metallic packing rings 57 surrounding the sleeve 34 and arranged to be received in an annular recess 58 in a cylindrical wall 59 which is disposed within and preferably formed integral with the cylindrical housing section 12. The cylindrical housing section 13

is provided with an internal annular recess 60 between the discharge spout 16 and that end adjacent the bearing cover 25, in which recess are received a plurality of non-metallic packing rings 61 fitting closely around the sleeve 34 and forming a seal preventing escape of coal laden air from the pressurized discharge spout 16 into the bearing cover 25 through the clearance provided between the inner end of the spout 16 and the sleeve 34.

From the above description it will be observed that the outer surface of the piston 28 is entirely out of bearing contact with the piston casing 11, thereby minimizing abrasion and scoring of the piston and rendering negligible the seizing or binding of the piston in the cylinder by reason of coal particles that find their way between the piston and cylinder. The construction, as described, also provides an effective seal between the non-pressurized coal intake and the pressurized coal discharge spout, permitting feeding of coal into a chamber under, for example, 150 lbs. pressure from a source of coal that is under atmospheric pressure, with a minimum of escape of pressure and a minimum of coal blow back. The differential in pressure between the intake and discharge spouts may be greater or less than 150 lbs., the above example being cited merely for illustrative purposes.

The coal receiving insert 52, as shown, is preferably formed as a separable removable unit from the piston head 29 so that it can be replaced, should wear or damage occur, without replacing the entire head, but it is apparent that the bore 30 of the head itself can be modified to form the coal receiving unit. In order to insure complete discharge of all the coal from the insert 52 into the outlet port 16, the side walls 62 and 63 are arranged to diverge from the upper receiving end of the insert 52 to the lower discharge end thereof.

At its open upper end, the insert 52 is provided with a plurality of laterally spaced, longitudinally extending vertical ribs 64 joining the side walls 62 and 63, as best shown in Figure 3. The tops of these ribs are flush with the arcuate upper edges of the side walls 62 and 63 that define the open top of the insert 52 and serve to prevent the upper edges of the sidewalls 62 and 63 from catching against the packing rings 57 as the piston 28 reciprocates. The open lower end of the insert 52 is provided with a plurality of similar ribs 65 which serve to prevent the lower edges of the sidewalls 62 and 63 from catching against the packing rings 57.

The inner cylindrical wall 59 of the cylindrical housing section 12 is provided with an arcuate wall extension 66 disposed below the intake spout 15. This arcuate wall 66 extends partially about the piston 28 and is integrally joined with the side wall of the intake spout 15, as clearly shown in Figure 3. Clearance is provided between the wall 66 and the piston 28 sufficient to eliminate surface contact therebetween as the piston 28 reciprocates without permitting any substantial leakage of coal from the bottom of the coal receiving insert 52.

Any small amount of coal that leaks between the piston 28 and the wall 66 drops into the passage 35 from which it is withdrawn through the port 67, connected in suitable manner with a source of suction.

In operation, with the piston 28 in the position shown in Figure 1, coal will drop by gravity through the spout 15 into the coal receiving insert 52. When the piston 28 moves to its ex-

treme opposite position, the open bottom of the insert 52 communicates with the pressurized spout 16. An annular passage 68 formed in the inner wall of the housing section 13 surrounds the piston 28 and communicates at its lower end with the spout 16 and at its upper end communicates with the open upper end of the insert 52. The pressure on the coal in the insert 52 is therefore the same at the top and bottom, permitting the coal to drop freely by gravity through the pressurized spout 16, connecting spout 18 and into a pressurized receptacle (not shown). In this latter position of the piston 28, it is apparent that the rings 57 and 61 by reason of their fitting closely against the sleeves 33 and 34, respectively, form a seal against release of pressure.

Upon the coal being discharged from the insert 52, a pressure will be built up in the insert 52, and to prevent the release of this pressure against the coal in the spout 15 when the piston 28 returns to its original position, thereby interfering with the free flow of coal into the insert, a vent 69 is provided which communicates with the annular passage 35. It is apparent then, that on the return stroke of the piston 28, the insert 52 will first communicate with the vent 69 before communicating with the spout 15, so that the pressure trapped in the insert 52 is released into the passage 35 and the port 67 which, as previously stated, is connected to a source of suction. Ports 53, best shown in Figures 2 and 6, connect the interior of the cover 25 with the passage 35, permitting air under pressure that leaks by the packing 61 to enter the passage 35 and to be withdrawn through the port 67.

Means is provided for conveniently lubricating various elements of the coal pump. The bearing 39 for the piston rod 37 is connected by means of a passage 76, formed in the bearing support 71, with a grease fitting 78, while the bearing 38 for the piston rod 36 is connected by means of a passage 79, formed in the transverse wall 20, with a

grease fitting 80. The wrist pin 51 is lubricated through the passage 81, formed in the piston rod 36, from a grease fitting 82. The crankshaft bearings 41 and 42 are lubricated through the passages 83 and 84 in the bearing covers 43 and 44, respectively, from respective grease fittings 85 and 86, and a grease fitting 87 provides lubrication for the connecting rods 46 and 47.

I claim:

10 Feed mechanism for delivering material from a non-pressurized zone into a pressurized zone, comprising a cylinder having offset intake and discharge openings communicating respectively with said non-pressurized and pressurized zones, a reciprocating piston in said cylinder, said piston being provided with a cavity communicating in one position of the piston in receiving relation with said intake opening and in another position of the piston in discharging relation with said discharge opening, said cavity expanding in cross sectional area from its intake to its discharging end, a plurality of spaced vertical longitudinally extending ribs bridging the receiving and discharge openings of the piston cavity, the outer 20 ends of said ribs being flush with the peripheral surface of said piston, and means within said cylinder between said openings and embracing said piston to form a seal between said cylinder and piston against escape of pressure from said pressurized zone to said non-pressurized zone.

EUGENE MARTIN.
